Primary Examiner — George D. Kirschbaum*Assistant Examiner* — Patricia K. Beard(74) *Attorney, Agent, or Firm* — Howard & Howard Attorneys PLLC(57) **CLAIM**

The ornamental design for a toy magnetic tile, as shown and described.

DESCRIPTION

FIG. 1 is a perspective view of a toy magnetic tile;

FIG. 2 is a top view thereof;

FIG. 3 is a bottom view thereof;

FIG. 4 is a front view thereof;

FIG. 5 is a rear view thereof;

FIG. 6 is left-side view thereof; and,

FIG. 7 is a right-side view thereof.

The broken lines in the drawings depict portions of the toy magnetic tile that form no part of the claimed design.

1 Claim, 5 Drawing Sheets(56)
